(57) **CLAIM**

The ornamental design for an adjustable label holder as shown and described.

DESCRIPTION

FIG. 1 is a top, back, right-hand side perspective view of an adjustable label holder showing our new design in a first state with an adjustable clip of the adjustable label holder is removably connected to a top of the adjustable label holder; FIG. 2 is a bottom, front, left-hand side perspective view thereof;

FIG. 3 is a back elevational view thereof;

FIG. 4 is a front elevational view thereof;

FIG. 5 is a right-side elevational view thereof;

FIG. 6 is a left-side elevational view thereof;

FIG. 7 is a top plan view thereof; and

FIG. 8 is a bottom plan view thereof.

FIG. 9 is a top, back, right-hand side perspective view of an embodiment of an adjustable label holder in a second state with the adjustable clip selectively mounting in a first position;

FIG. 10 is a bottom, front, left-hand side perspective view thereof;

FIG. 11 is a back elevational view thereof;

FIG. 12 is a front elevational view thereof;

FIG. 13 is a right-side elevational view thereof;

FIG. 14 is a left-side elevational view thereof;

FIG. 15 is a top plan view thereof; and

FIG. 16 is a bottom plan view thereof; and

FIG. 17 is a bottom, front, right-hand side perspective view thereof in an environment of use.

FIG. 18 is a top, back, right-hand side perspective view of an embodiment of an adjustable label holder in a third state with the adjustable clip selectively mounting in a second position; and,

FIG. 19 is a top, back, left-hand side perspective view thereof.

The broken lines shown in FIG. 17 illustrate the environment in which the adjustable label holder may be used, including a shelf and product label, which forms no part of the claimed design.
